[57] CLAIM

The ornamental design for physiological monitoring device housing, as shown and described.

DESCRIPTION

FIG. 1 is a perspective front view of a physiological monitoring device housing showing our design;

FIG. 2 is a side view of the physiological monitoring device housing of FIG. 1;

FIG. 3 is a top plan view of the physiological monitoring device housing of FIG. 1;

FIG. 4 is a rear end view of the physiological monitoring device housing of FIG. 1;

FIG. 5 is a front end view of the physiological monitoring device housing of FIG. 1.

The stethoscope shown in broken lines is for illustrative purposes only.
